ATTORNEY

UNITED STATES PATENT OFFICE.

JACOB J. BURKHARTZMEYER, OF FARIBAULT, MINNESOTA.

PROJECTILE.

1,278,104.

Specification of Letters Patent. Patented Sept. 10, 1918.

Application filed September 28, 1917. Serial No. 193,775.

To all whom it may concern:

Be it known that I, JACOB J. BURKHARTZMEYER, a citizen of Russia, residing at Faribault, in the county of Rice and State 5 of Minnesota, have invented certain new and useful Improvements in Projectiles, of which the following is a specification.

This invention has relation to explosive containing projectiles adapted to be discharged from a gun, and has for an object 10 to provide a projectile constructed in a manner to cause ignition of its explosive contents after the projectile has penetrated its object.

15 Another object of the invention is to provide a new and novel exploding mechanism for an explosive containing shell.

A still further object of the invention is 20 to provide an explosive containing shell having the characteristics above named, and means for preventing accidental explosion of the shell during handling.

A still further object of the invention is 25 to provide a shell having its nose formed in a peculiar manner to permit rapid and effective penetration thereof in the object against which it is directed.

In addition to the foregoing, this invention comprehends improvements in the details of construction and arrangement of parts, as will be hereinafter described and particularly pointed out in the appended claims.

In the accompanying drawings, wherein 35 similar and corresponding parts are designated by the same characters of reference throughout the several views in which they appear;

Figure 1 is a view in longitudinal section 40 of an explosive containing shell constructed in accordance with my invention, and

Figs. 2 and 3 are transverse sections taken on the line 2—2 and 3—3 respectively of the preceding figure, and

45 Fig. 4 is a view in perspective of a band for encircling the shell.

With reference to the drawings, 10 indicates the shell proper, open at its rear end, and said end reduced circumferentially as at 50 11 to receive a removable cap 12 which serves as a closure for the rear end of the shell.

A transverse partition 14 is located within the shell at a point approximately intermediate its ends to define a compartment 15 in 55 the forward end of the shell which is filled with explosive. A compartment 16 is de-

fined at the opposite side of the partition to contain the mechanism whereby discharge within the forward compartment is exploded. This mechanism includes a disk 17 60 mounted centrally upon the rear face of the partition and having three, more or less openings arranged in uniform spaced relation which openings coincide with similar openings provided in the partition. The 65 disk may be provided with circumferential flanges 18 to surround each opening whereby to form a guide for pins 19 which extend through the flanges and openings and are provided upon their ends which project 70 within the compartment 16 with eyes 20. The opposite ends of the pins 19, or those ends which extend into the forward compartment of the shell are frictionally held within caps 21 which are filled with fulminate, or some other chemical composition 75 which will explode when abraded.

A base plate 22 is mounted within the cap 12 at the rear end of the shell and three standards 23 are mounted on said base plate 80 to support small pulleys 24 in pivotal relation. In radial alinement with each standard 23, the container 10 of the shell is formed with an opening 25. Mounted on the base plate adjacent each opening is an 85 oscillatably mounted member 26, each member being substantially elliptical in configuration and provided with an extension 27. Each oscillatably mounted member 26 is pivoted at a point adjacent one end as at 90 28 between and upon a pair of spaced ears 29 which are formed integral with the base plate 22 whereby the oscillatably mounted members may be moved from a position within the shell to a position wherein they 95 project partly through the openings 25 in the side of the shell. What may be termed a trigger is indicated at 30, and one is provided for each oscillatably mounted member, the triggers being mounted at a point 100 adjacent one of their ends upon the extensions 27 of the members 26, the opposite ends of the triggers being curved and directed forwardly. The end of each trigger adjacent its point of connection to the extension 27 is connected to a flexible element 31 at one end of said element, the element then being passed around an adjacent pulley 24 and connected at its opposite end to the eye 20 of one of the pins 19. Each oscillatably mounted member is formed with a laterally extending flange 32 which is engage-

able by a leaf spring 33 mounted upon a suitable support 33' shown in Fig. 2 whereby to urge the members 26 outward through the openings in the side of the shell. When 5 the shell is being handled, before its entrance into the gun, a band of metal or the like is slid on the shell or embraced thereabout to cover the openings 25 whereby to retain the oscillatably mounted members 26 and the triggers 30 entirely within the shell whereby the flexible elements 31 will be relieved of strain.

When the shell is inserted in the breach of a gun, the band will be slid rearwardly 15 from the shell by engagement thereof with the rear end of the gun. The oscillatably mounted members 26 and triggers 30 will then engage the bore of the gun but will still be retained in an inward position. 20 When the shell leaves the gun a rotary motion is imparted thereto by means of the rifling in the bore of the gun whereupon the oscillatably mounted members 26 are thrown outward by action of the leaf spring 33, and 25 the triggers 30 are thrown outward by action of the centrifugal force due to the rotation of the shell in its flight. It will be noted that the parts having assumed the position shown in Fig. 1, the curved ends of 30 the triggers 30 will be projected forwardly whereupon after penetration of the shell in its object, the triggers will be engaged against the edges of the openings in the object made by the entrance of the shell so as 35 to place the flexible elements 31 under strain whereby the pins 19 are withdrawn from the disk 17 supporting the same. Owing to the rapid withdrawal of the pin from the caps 21 mounted thereon, the caps being of a size 40 too large to permit them to be drawn through the openings in which the pins are held, the fulminate within the caps is ignited thereby igniting the charge whose effect will be more pronounced because of the location of the 45 shell entirely within the object, as for instance the hull of a vessel.

While I have illustrated and described my invention with some degree of particularity, I realize that in practice various 50 alterations therein may be made, and I therefore reserve the right and privilege of changing the form of the details of construction, or otherwise altering the arrangement of the correlated parts, without de-

parting from the spirit of the invention or 55 the scope of the appended claims.

Having thus described my invention what I claim as new and desire to secure by Letters Patent is:—

1. In an explosive containing shell having 60 a plurality of circumferentially spaced openings, a plurality of members mounted within the shell adjacent the openings, means for urging the members outward, a band encircling the shell to retain the members within 65 the shell, triggers mounted on the members adapted, when the band is removed to be projected from the sides of the shell through the openings whereby they may engage an object after the shell has penetrated the 70 same, and means operable upon movement of the triggers for igniting the charge.

2. In an explosive containing shell having a plurality of circumferential openings, a member mounted for oscillation opposite 75 each opening within the shell, resilient means urging the members outward, a band encircling the shell to retain the members within the shell, a trigger mounted on each member adapted, when the shell is rotated 80 to be projected partly through the openings, and means operable upon movement of the triggers for exploding the charge.

3. In an explosive shell having a plurality of circumferentially spaced openings, a plurality of members mounted in the shell, one adjacent each opening, each member being substantially elliptical in configuration, a curved flange laterally extending from one edge of each member, a leaf spring stationarily mounted within the shell engaging the flange to urge the members outward, a tangentially extending arm projecting from each member, a trigger pivotally mounted on the extremity of each arm adapted to be projected through the opening by centrifugal force, pulleys mounted within the shell adjacent each member, igniting elements and flexible elements connecting said triggers with said igniting elements, and passing 90 around the pulleys.

In testimony whereof I affix my signature in presence of two witnesses.

JACOB J. BURKHARTZMEYER.
